LET-OFF MECHANISM FOR LOOMS.

SPECIFICATION forming part of Letters Patent No. 783,183, dated February 21, 1905.

Application filed November 18, 1904. Serial No. 233,260.

To all whom it may concern

Be it known that I, CLARE H. DRAPER, a citizen of the United States, and a resident of Hopedale, county of Worcester, State of Massachusetts, have invented an Improvement in Let-Off Mechanism for Looms, of which the following description, in connection with the accompanying drawings, is a specification, like characters on the drawings representing like parts.

In the well-known "Bartlett" let-off motion the whip-roll or warp-guide is moved or rocked downward at each pick by the tension of the warp, a suitable connection setting a pawl (coöperating with a ratchet through which the warp-beam is rotated) in such manner that a greater or less number of ratchet-teeth will be delivered when the pawl is moved forward to a fixed point on its operating stroke. The greater the warp tension the larger the number of teeth which will be taken by the pawl when set, and a correspondingly greater delivery of the warp will be effected, the pawl being moved to a fixed point at each stroke by a connection between the pawl-carrier and a moving part of the lay. This let-off motion is defective because of the increased strain upon the warp due to the greater movement of the whip-roll when the beam is nearly empty, for as the diameter of the yarn mass on the beam decreases a greater number of ratchet-teeth must be included in the stroke of the pawl to compensate for such decrease, and this greater movement of the whip-roll requires greater power to effect the same. Such increased strain or tension on the warp results in narrower cloth, causes thin places at the time of filling-changing, and increases warp breakage. In United States Patent to Draper and Roper, No. 647,815, dated April 17, 1900, these objectionable features were overcome by the employment of novel means controlled by the warp tension and the diameter of the yarn mass on the beam to determine the starting-point of each stroke of the pawl. Such means included a compound pawl-carrier with a relatively movable connection for the members thereof, one of said members being

moved in setting the pawl by means governed by the warp tension, while the position of the connection between the members of the pawl-carrier was determined by a controlling device dependent upon the diameter of the yarn mass on the beam. This let-off mechanism has been highly satisfactory in operation; but my present invention has for its object the production of a simpler form of let-off mechanism possessing the various advantageous features of such patented structure and free from the objections of the Bartlett type of let-off.

I have in the present embodiment of my invention eliminated the compound pawl-carrier and the follower which coöperates with the periphery of the yarn mass on the beam, together with the connecting devices between the follower and the compound pawl-carrier, the starting-point of each stroke of the pawl being determined herein by means acting wholly through the whip-roll, so that such starting-point is located in conformity with the combined action of the warp tension and the diameter of the yarn mass on the beam.

Figure 1 is a right-hand side elevation of a loom with let-off mechanism embodying one form of my present invention applied thereto. Fig. 2 is a detail viewed from the opposite side of the loom of the rocking support for the whip-roll and some of the adjacent parts to be described; and Fig. 3 is a rear view, centrally broken out, of the whip-roll and adjacent parts.

The warp-beam B, having an attached large gear B', the driving-shaft B^x, carrying in practice a pinion (not shown) in mesh with the beam-gear B' and having loosely mounted upon it the ratchet B^z, the friction clamp or brake F to coöperate with the ratchet-hub, the speed-reducing gearing inclosed within the casing G, forming a part thereof and connected by hub g^x with the shaft B^x, and the arms b¹⁶ and g¹³, slidably connected with a fixed stud E on the loom side, may be and are all substantially as in United States Patent of Roper, No. 744,941, said patent being based upon the prior patent, No. 647,815, hereinbefore referred to.

Herein the let-off pawl d^x , which coöperates with and operates the ratchet B^y , is mounted on a pawl-carrier 1, loosely mounted to rock upon the shaft B^x adjacent the ratchet 5 and having a depending arm 2 pivotally connected with a link d^6 , provided at its forward end with an elongated eye d^5 to receive a pin d^4 on the lay-sword A^x , substantially as in Patent No. 744,941 referred to. The forward 10 beat of the lay acts through the link to impart the feed or operating stroke to the pawl d^x and moving it to a fixed point on each stroke. Brackets 3 on the loom sides above the warp-beam support a transverse horizontal 15 rock-shaft 4, having secured to it by set-screws 5^x , Fig. 3, upturned arms 5, provided at or near their upper ends with bearings for the journals w^x of the whip-roll or warp-guide W, over which the warp w passes from the 20 beam to the lease-rods L and harnesses H, Fig. 1. On the end of the shaft adjacent the right-hand side of the loom, as herein shown, an upturned arm 6 is adjustably secured by a set-screw 7, said arm having an 25 elongated longitudinal slot 8, in which is adjustably secured a stud 9, on which is pivoted the upper end of a link 10, its lower end being pivotally connected at 11 with the pawl-carrier 1 between the pawl and the shaft B^x , 30 on which said pawl-carrier rocks. Adjacent the whip-roll-supporting arm 5 near the upturned arm 6 the hub of an arm 12 is mounted on the shaft 4, said arm being inclined upward and forward and having its free end 35 laterally offset at 13 to receive a threaded stud 14, screwed into the offset and adapted to bear against the adjacent arm 5, so that by setting up or letting off the stud the angle between the arms 5 and the arm 12 will be increased 40 or diminished. A set-screw 15, Fig. 1, holds the arm 12 securely upon the rock-shaft 4 when adjusted, and a check-nut 16 is preferably provided for the stud 14. The tension-spring S is secured at one end to the loom. 45 side and at its other end it is attached to a downwardly and rearwardly extended arm 17, secured to the rock-shaft 4 by a set-screw 18 Fig. 2.

It will be manifest from an inspection of the 50 drawings that the warp tension will rock the whip-roll forward at each pick, and the greater the tension of the warp the greater will be the amplitude of angular movement of the whip-roll as it rocks on the shaft 4 as a fulcrum. Consequently the arm 6 will be correspondingly rocked to a greater or less extent in conformity with the warp tension, and the link 10 will depress the pawl-carrier 1 more or less to determine or fix the starting-point 55 for each operating stroke of the let-off pawl d^x . The greater the angle between the portions w' of the warp leading from the yarn mass N on the beam of the whip-roll and from the latter forward at w the nearer will the resultant of the forces acting upon the whip-

roll approach its fulcrum—viz., the rock-shaft 4—and for a given warp tension the less will be the amplitude of the angular movement of said whip-roll. Such angle will be greatest when the beam is full, and, conversely, 70 it gradually diminishes as the diameter of such yarn mass decreases. As the upper side w of the warp angle remains substantially fixed, while the opposite side w' (formed by the warp leading from the beam to the whip-roll) changes its position, it follows that the resultant of the forces acting upon the whip-roll to rock it will gradually move away from the fulcrum on which the whip-roll rocks. Consequently as the diameter of the 80 yarn mass on the beam decreases the whip-roll will be rocked a greater distance, but without increasing the strain upon the warp at each pick, inasmuch as the increased leverage effects the desired increased movement without any additional warp strain, and such augmented amplitude of movement of the whip-roll will act through arm 6 and link 10 to give a greater movement to the pawl-carrier 1. The pawl d^x will then be set at a point 90 farther back and the operating stroke of the pawl will include more of the ratchet-teeth, producing the required increase in the length of warp let off from the beam. As a matter of fact, the rate of change in the position of the 95 part w' of the warp varies from full to empty beam for a uniform rate of decrease in the diameter of the yarn mass—that is to say, the rate of change in the angular position of the part w' will be very much greater per inch, say, of 100 diametrical decrease in the yarn mass when the unwinding of the beam begins than it will be when the beam is nearly empty, or, in other words, the angle inclosed by the portions $w w'$ of the warp decreases at a faster 105 rate during the early unwinding of a beam than at the later unwinding. This irregularity of variation in the warp angle should be compensated for in order to obviate any requirement for adjustment of the let-off during 110 the complete unwinding of a beam, and such compensation is attained by the connection between the whip-roll and the pawl-carrier, such connection comprising the arm 6 and link 10. It will be manifest that the more nearly the 115 arm 6 approaches the horizontal as it is moved downward by the forward movement of the whip-roll the greater will be the movement of the pawl to the starting-point of its effective stroke, and such stroke will be longer. The setting stroke for the pawl will be less, however, for a given angular movement of the arm 6 when the latter is at or about the position shown in Fig. 1 than it will be 120 for the same angular movement of the arm 6 when nearer horizontal position. In other words, the rate of variation of the setting stroke does not increase until a very considerable increase in the regular movement of the arm 6 is effected, and this increase in angular 125 130

movement of said arm is not effected until the unwinding has progressed quite far, so the increase in the rate of variation of the setting stroke of the pawl does not occur until the 5 rate of change in the position of the part w' of the warp has reached substantially its minimum. Thus the rapid rate of change in the one is automatically compensated for by the slow rate of variation of the other, and 10 vice versa, eliminating the necessity for manual adjustment during the unwinding of the beam.

The theory of operation may be stated thus: Supposing the warp pull or tension to be uniform, the whip-roll should be swung through 15 increasingly greater arcs as the yarn mass decreases, and the arm 6 should correspondingly be moved through greater angles to thereby impart by degrees a lengthening stroke to the pawl d^x as the beam empties. An increasing angular movement of the beam should result, letting off the proper length of yarn at each pawl-stroke, increasing little by 20 little as the diameter of the yarn mass decreases; but if the angle between w and w' decreases at a more rapid rate at the beginning 25 of the unwinding, as is the fact, the corresponding arcs of movement of the whip-roll would at first appear to be so long that there 30 would be a tendency to impart too long a stroke to the pawl, which would result in letting off the yarn too rapidly, presupposing the rate of increase in the pawl-strokes to be regular. At the beginning of the unwinding, 35 however, the movements of the whip-roll are not great enough to impart sufficient angular movement to the arm 6 to effect any practical increase of the pawl-stroke, while later as the beam empties the increasing arcs of movement of the whip-roll impart greater angular 40 movements to the arm 6 and the pawl-strokes are gradually lengthened thereby at a more rapid rate as the rate of decrease of the angle between w and w' diminishes. The desired 45 compensation is thus effected automatically and the yarn is neither let off too rapidly at first nor too slowly at the last. I am thus enabled to secure substantially the same warp tension during each pick from the full to the 50 empty beam with very simple and direct-acting means, the warp tension and the diameter of the yarn mass on the beam acting conjointly and wholly through the whip-roll to determine the starting-point of each stroke of the 55 pawl.

The adjusting-screw 14 is provided with a head 14^x , by which the screw can be readily turned with the aid of a wrench or similar tool to change the angle of the arms 5 with relation 60 to the arm 6, enlargement of the angle serving to shorten the feed-stroke of the pawl while decrease of the angle lengthens the stroke. When such adjustment is to be made, the set-screws 5 x are loosened and the whip-roll is 65 moved with or against the pull of the warp,

according to the direction in which the screw 14 is turned, the adjustment so made making no change in relation between the pawl-carrier and arm 6. If a change in the latter relation is desired, it can be effected by adjustment of the stud 9 in the slot 8. 70

My invention is not restricted to the precise construction and arrangement herein shown and described, as the same may be modified in various particulars by those skilled in the art 75 without departing from the spirit and scope of my invention.

Having fully described my invention, what I claim as new, and desire to secure by Letters Patent, is— 80

1. In let-off mechanism for looms, a warp-beam, means to rotate it, including a ratchet and pawl, an actuating device to move the pawl to a fixed point at each operating stroke, a rocking whip-roll the amplitude of whose angular movement is controlled conjointly by the warp tension and the diameter of the yarn mass on the beam, to maintain a substantially uniform warp tension throughout the unwinding, and means intermediate said whip-roll 85 and pawl to determine the starting-point of each stroke of the pawl in conformity with the angular movement of the whip-roll. 90

2. In let-off mechanism for looms, a warp-beam, means to rotate it, including a ratchet and pawl, a pawl-carrier, an actuating device therefor to move the pawl to a fixed point at each operating stroke, a rocking whip-roll the amplitude of whose angular movement is controlled conjointly by the warp tension and the diameter of the yarn mass on the beam, and means intermediate the whip-roll and pawl-carrier and directly connected with the latter to determine the starting-point of each stroke of the pawl in conformity with the angular 100 movement of the whip-roll. 105

3. In let-off mechanism for looms, a warp-beam, means to rotate it, including a ratchet and pawl, a pawl-carrier, an actuating device therefor to move the pawl to a fixed point at each operating stroke, a rocking whip-roll the amplitude of whose angular movement is controlled conjointly by the warp tension and the diameter of the yarn mass on the beam, means intermediate the whip-roll and pawl-carrier 110 and directly connected with the latter to determine the starting-point of each stroke of the pawl in conformity with the angular movement of the whip-roll, and an adjusting device for said means. 115

4. In let-off mechanism for looms, a warp-beam, means to rotate it, including a ratchet and pawl, an actuating device to move the pawl to a fixed point at each operating stroke, up-turned arms fulcrumed above the beam, a 125 whip-roll mounted on said arms and adapted to be rocked by or through the warp, the amplitude of angular movement of the whip-roll being controlled conjointly by the warp tension and the diameter of the yarn mass on the 130

beam, to maintain a substantially uniform warp tension throughout the unwinding, and means intermediate the whip-roll and pawl to determine the starting-point of each stroke of the latter in conformity with the angular movement of the whip-roll.

5. In let-off mechanism for looms, a warp-beam, means to rotate it, including a ratchet and pawl, an actuating device to move the pawl to a fixed point at each operating stroke, a rock-shaft mounted above the warp-beam and having rigidly - attached upturned arms, a whip-roll mounted in said arms and adapted to be rocked about the shaft as a center, the angular movement of the whip-roll varying in accordance with the warp tension and gradually increasing by or through the decrease of the diameter of the yarn mass on the beam, and means intermediate the whip-roll and pawl to fix the starting-point of the pawl-stroke according to the amplitude of the corresponding angular movement of the whip-roll.

6. In let-off mechanism for looms, a warp-beam, means to rotate it, including a ratchet and pawl, an actuating device to move the pawl to a fixed point at each operating stroke, a rock-shaft mounted above the warp-beam and having rigidly - attached upturned arms, a whip-roll mounted in said arms and adapted to be rocked about the shaft as a center, the angular movement of the whip-roll varying in accordance with the warp tension and gradually increasing by or through the decrease of the diameter of the yarn mass on the beam, an arm mounted on the shaft and operatively connected with the pawl, and means to vary the angle between said arm and the whip-roll-supporting arms, the connection between the adjustable arm and the pawl determining the starting-point of the pawl-stroke in conformity with the angular movement of the whip-roll.

7. In let-off mechanism for looms, a warp-beam, means to rotate it, including a ratchet and pawl, a pawl-carrier, an actuating device therefor to move the pawl to a fixed point at each operating stroke, a rock-shaft mounted above the beam and having attached upturned arms, a whip-roll mounted in the latter and adapted to be rocked about the shaft as a center, the amplitude of angular movement of the whip-roll varying with variations in warp tension and having a gradual increase by or

through the decrease of the diameter of the yarn mass on the beam, an arm angularly adjustable on the rock-shaft, and a link pivotally connecting said arm and the pawl-carrier, to fix the starting-point of the latter for each operating stroke of the pawl in conformity with the corresponding angular movement of the whip-roll.

8. In let-off mechanism for looms, a warp-beam, means to rotate it, including a ratchet and pawl, an actuating device to move the pawl to a fixed point at each pick, a rocking whip-roll, and means acting wholly through said whip-roll to determine the starting-point of each stroke of the pawl in conformity with the combined action of the warp tension and the diameter of the yarn mass on the beam, to thereby maintain a substantially uniform warp tension throughout the unwinding.

9. In let-off mechanism for looms, a warp-beam, means to rotate it, including a ratchet and pawl, actuating means for the latter, including a rocking whip-roll, and means depending on the angle of the warp between the beam and the whip-roll to effect increased movement of the whip-roll while the tension of the warp remains substantially uniform.

10. In let-off mechanism for looms, a warp-beam, means to rotate it, a movable whip-roll, to govern the amplitude of angular movement of the beam, and means to vary the movement of the whip-roll by or through a change in the position of the plane of the warp between the whip-roll and the beam while the tension of the warp remains substantially uniform.

11. In let-off mechanism for looms, a warp-beam, means to rotate it, including a ratchet and a pawl, actuating means for the latter, including a rocking whip-roll, and means governed by or through the movement of the whip-roll to compensate for irregular variation in the angular position of the warp between the full and the empty beam and thereby prevent variation in warp tension.

In testimony whereof I have signed my name to this specification in the presence of two subscribing witnesses.
